ROTARY DIET REMINDER DEVICE

Marcel Neumann, 7240 Lowell, Lincolnwood, Ill. 60646,
and Burton L. Siegal, Skokie, Ill.; said Siegal assignor
to said Neumann

Filed July 15, 1970, Ser. No. 23,952

Term of patent 14 years

Int. Cl. D20—99

U.S. Cl. D52—6

FIG. 1 is a top plan view of a rotary diet reminder device illustrating our new design;

FIG. 2 is a side elevational view of the device;

FIG. 3 is a sectional view taken along the line 3—3 of FIG. 1 in the direction indicated generally.

The rear surface of the device is plain.

We claim:

The ornamental design for a rotary diet reminder device, as shown and described.
